UNITED STATES PATENT OFFICE.

ANDERS ANDERSEN PINDSTOFTE, OF COPENHAGEN, DENMARK.

REVOLVING BOTTLE-CLEANING MACHINE.

1,246,460.

Specification of Letters Patent. Patented Nov. 13, 1917.

Application filed February 10, 1915. Serial No. 7,343.

To all whom it may concern:

Be it known that ANDERS ANDERSEN PINDSTOFTE, manufacturer, subject of the Kingdom of Denmark, residing at No. 62 Frederiksberg Alle, Frederiksberg, near Copenhagen, Denmark, has invented certain new and useful Improvements in Revolving Bottle-Cleaning Machines, of which the following is a specification.

10 The present invention has for its object an improved revolving bottle cleaning machine of that class or type in which the interiors of the bottles are cleaned by means of brush-spindles, mounted radially, independently 15 of one another, in removable bearings around a vertical shaft; the brush-spindles are rotated by said shaft and moved around the same, so that the attendant, from the position at which he is stationed relative to 20 the machine, can both insert the bottles on and remove them from said brush-spindles. A machine of this type is shown and described in my prior Patent, No. 944,986, granted December 28, 1909, upon which the 25 present invention is an improvement. In such machines, the outer faces of the bottle bottoms are cleaned by means of bottom-brushes pivotally mounted on the brush-spindle bearings, while the outsides and 30 necks of the bottles are cleaned by means of one or more revolving brush-rollers mounted above the brush-spindles.

Hitherto, in such machines, the removable bearings of the brush-spindles have been 35 pivotally mounted in a frame which is rotated by friction from the constantly-revolving vertical shaft, while the brush-spindles are caused to rotate in their bearings by means of friction rollers fixed 40 to the rear of the spindles; these friction rollers, when a bottle is inserted on a brush-spindle, owing to the weight of the bottle and to the mounting of the bearing, are pressed against a friction disk fixed to 45 the vertical shaft above the bearings. Such arrangement has, however, the drawback that the brush-spindles, as the friction rollers and the friction disk become worn, will assume a more and more outwardly and 50 downwardly inclined position when the bottles are inserted upon them, with the result that the interiors of the bottles will not be equally cleaned throughout, unless the machine-parts exposed to wear are correspondingly adjusted.

According to the present invention, this

drawback is avoided by mounting the bearings of the brush-spindles freely and loosely in guides carried by the frame, which latter is rotated by friction from the vertical drive 60 shaft. The front end of each of the bearings is adjustably supported upon said frame by means of a screw carried thereby, so that by adjusting said screws, the bearings may be moved up and down, and thereby the 65 positions of the brush-spindles may be varied to correspond with the dimensions of the bottles. In accordance with the invention, the friction rollers of the brush-spindles rest upon the friction disk fixed to the 70 vertical drive shaft, so that wear of the friction rollers and of the friction disk can always be equalized by an adjustment of the adjusting-screws of the bearings.

In machines of this kind heretofore 75 known, the pivotally-mounted bottom-brushes and the pivotally-mounted funnels that guide the mouths of the bottles during their insertion on the brush-spindles are fixed to brackets on the bearings of the 80 brush-spindles. This arrangement has, however, several drawbacks, which in the present invention are avoided by mounting these bottom-brushes and guide-funnels on a special ring carried by brackets fixed to the 85 above-mentioned rotatable frame which supports the front ends of the bearings of the brush-spindles and carries the guides for 90 said bearings, so that said ring rotates with the bearings.

The annexed drawing illustrates an embodiment of the invention.

Figure 1 is a fragmental vertical section;

Fig. 2 is a fragmental side elevation;

Fig. 3 is a vertical section, showing a detail;

Fig. 4 is a fragmental plan view; and Fig. 5 is an enlarged detail view, in side elevation, of one of the guide-funnels.

The machine consists of a frame *a*, provided at its top with a bearing for a vertical shaft *c*, which is constantly rotated, in any suitable manner, as for instance by means of the pulley *b*, from a main shaft or other source of power, (not shown). The shaft *c* 100 carries a friction disk *d*, and its lower portion is inserted into a hollow shaft *f* mounted in a bearing *e*, the top of said shaft *f* carrying a disk-like frame *g* which is formed with a depending peripheral flange or rim. 105

Below this frame *g* the shaft *f* is further provided with two friction-disks *i*, which are

- tightened together by means of screws and wing-nuts *h*, these disks *i* clamping between them a toothed ring *j* which meshes with a pinion *l* fixed to a shaft *k*. The latter is 5 constantly rotated by means of a pulley *k'* from the main shaft, so that the frame *g* is rotated around the shaft *c* owing to the friction between the toothed ring *j* and the friction disks *i*.
- 10 The brush-spindles *m*, which serve to clean the interiors of the bottles, are arranged radially around the shaft *c* in bearings *n*, the front ends of which are adjustably supported with relation to the frame *g* by means of 15 screws *o* threaded into said frame. The rear portions of the bearings are freely and loosely mounted in guides *p* fixed to the frame *g*, so that the bearings can be adjusted in said guides by means of the adjusting 20 screws, thereby vertically adjusting the brush-spindles into the positions corresponding to the dimensions of the bottles treated. Each of the brush-spindles is provided with a friction roller *q*, which is pressed against 25 the friction-disk *d* by the weight of the bearing *n*, so that the brush-spindles are rotated when the drive shaft *c* is rotated.

By means of brackets *r*, (Figs. 3 and 4), a ring *s* is fixed to the frame *g*. This ring 30 carries, adjacent to each of the brush-spindles, a pivotally-mounted bottom-brush *t* and a pivotally-mounted, guide-funnel *u*, which latter is of the type shown and described in my said patent and acts in the manner there- 35 in set forth. The bottom-brushes are pressed against the bottoms of the bottles and maintained in this position by a guide-rail *v*, (Fig. 4).

During working, the bottles inserted on 40 the brush-spindles are supported by a ring *z*, which does not revolve.

The operation of the machine is as follows:—

Before the operation begins, the bearings 45 *n* are adjusted by means of the screws *o* to give the brush-spindles *m* such a position that the bottles subsequently inserted thereon will be supported upon the above-mentioned ring *z*. Then the machine is started, 50 and the bottles are successively inserted on the brush-spindles. During the movement of the frame *g*, the bottom-brushes *t* are successively pressed against the bottoms of the bottle by the guide-rail *v*. The bottle rolls 55 along the rail *z*, and the brush spindle *m* is rotated by its friction-roller *q*, which latter rests upon the friction disk *d* fixed to the constantly rotating shaft *c*.

By the invention the following new technical effects are obtained:

1. The ring *z* on which the bottles roll does not need to be adjusted, but can always have the same position regardless of the dimensions of the bottles to be cleaned and of the wear of the several parts of the machine. 65

2. The bearings *n* of the brush-spindles are loosely mounted, so that they can be easily removed and renewed, and they are only pressed against the revolving supporting friction disk by a constant pressure pro- 70 portionate to their own weight.

3. The front ends of the brush-spindle bearings can easily and readily be adjusted in such a manner that the said brush-spindles always can be brought into a position 75 corresponding to the dimensions of the bottles treated.

I claim as my invention:—

1. In a revolving bottle-cleaning machine, the combination of a vertical drive shaft; 80 means for rotating said shaft; a vertical drive shaft disposed in axial alinement with the first-named shaft; means for rotating the second named shaft independently of the first-named shaft; a frame fixed to the sec- 85 ond-named shaft; a plurality of radial brush-spindles; a plurality of bearings; one for each brush-spindle; guides for the rear ends of said bearings carried by said frame; adjusting screws, one for each bearing, sup- 90 porting and guiding the front ends of said bearings and attached to said frame; a friction roll fixed to each brush-spindle; and a friction disk fixed to the first-named shaft below said friction disk and in engagement 95 therewith.

2. In a revolving bottle-cleaning machine, the combination of a vertical drive shaft; means for rotating said shaft; a vertical drive shaft disposed in axial alinement with 100 the first-named shaft; means for rotating the second named shaft independently of the first-named shaft; a frame fixed to the sec- 105 ond-named shaft; a plurality of radial brush-spindles; a plurality of bearings, one for each brush-spindle; guides for the rear ends of said bearings carried by said frame; adjusting screws, one for each bearing, sup- 110 porting and guiding the front ends of said bearings and attached to said frame; a friction roll fixed to each brush-spindle; a friction disk fixed to the first-named shaft below said friction disk and in engagement 115 therewith; a ring fixed to said frame; and a pivotally-mounted bottom brush for each brush-spindle carried by said ring.

In testimony whereof he affixes his signature in presence of two witnesses.

ANDERS ANDERSEN PINDSTOFTE.
